DISTANCE-TYPE PRODUCT-RESPONSIVE
RELAY

Shirley L. Goldsborough, Basking Ridge, N. J., assignor to Westinghouse Electric Corporation, East Pittsburgh, Pa., a corporation of Pennsylvania

Application February 16, 1945, Serial No. 578,158

2 Claims. (Cl. 175—294)

1

My invention relates to a new wattmetric type of adjustable-characteristic modified impedance relay for protecting alternating-current lines against faults.

The principal object is to provide means for exciting the two windings of a product-responsive or wattmetric relay so as to be adjustably responsive to the vector sum of a line-current and a line-voltage, in each case, with means for varying the relative phase-angles and the magnitudes of the several responses in such manner as to provide independent adjustments of the several characteristics of the response-circle.

A further object is to provide a modified-impedance relay having means for independently varying the slope of its center-line, or line joining the center of the circle and the origin of the rectangular coordinates of line-resistance and line-reactance, and also independently adjusting the two intercepts of the circle on the center-line.

With the foregoing and other objects in view, my invention consists in the combinations, systems, parts and methods hereinafter described and claimed, and illustrated in the accompanying drawing, wherein

Fig. 1 is a diagrammatic view of circuits and apparatus embodying my invention in an illustrative form of embodiment utilizing a cosine-type wattmetric or directional relay-element;

Fig. 2 is a similar view of a modified form of embodiment utilizing a sine-type wattmetric or directional relay-element, and

Fig. 3 is a curve-diagram illustrating a typical response-circle and showing the characteristics which can be independently adjusted in accordance with my invention.

My present invention is of general application to any wattmetric or product-responsive relay, whether of the sine-type, or cosine-type, or any intermediate type. Such a relay utilizes two alternating magnetic fluxes ϕ_1 and ϕ_2 having a phase-angle ϕ_0 between them, and it develops a maximum torque at a certain characteristic phase-angle ϕ_r between said fluxes. For a cosine-responsive element, ϕ_r is 0; for a sine-element $\phi_r=90^\circ$; for a 45° -element, $\phi_r=45^\circ$, etc. The torque of such a wattmetric element is therefore

$$T = \phi_1 \phi_2 \cos(\phi_0 - \phi_r) \quad (1)$$

In order to obtain a distance-response or an impedance-response, I make both of these fluxes responsive to both a line-derived voltage E and a line-derived current $I \angle \theta$. In order to adjust the relay response-characteristics, in the most gen-

eral case, I provide means for adjusting both the phase and the magnitude of each of the responses. The two fluxes may be written

$$\phi_1 = gE \angle S - gmI \angle \theta \quad (2)$$

$$\phi_2 = hE \angle (S-U) - hnI \angle (\theta-V) \quad (3)$$

The total relay-torque is the sum of the products of the different pairs of terms, each multiplied by $\cos(\phi_0 - \phi_r)$, where ϕ_0 is the angle between the two terms being multiplied. The torque is therefore

$$T = gh[E^2 \cos(U - \phi_r) - nEI \cos(S + V - \theta - \phi_r) - mEI \cos(\theta - S + U - \phi_r) + mnI^2 \cos(V - \phi_r)] \quad (4)$$

At the balance-point of the relay, this torque T will be zero. Dividing through by I^2 , and remembering that

$$\frac{E^2}{I^2} = R^2 + X^2 \quad (5)$$

$$\frac{E}{I} \cos \theta = R \quad (5)$$

$$\frac{E}{I} \sin \theta = X \quad (5)$$

the balance-point is found to occur when

$$0 = (R^2 + X^2) \cos(U - \phi_r) - nR \cos(S + V - \phi_r) - nX \sin(S + V - \phi_r) - mR \cos(S - U + \phi_r) - mX \sin(S - U + \phi_r) + mn \cos(V - \phi_r) \quad (6)$$

If $\cos(U - \phi_r)$ is not zero,

$$35 \quad \left[R - \frac{n \cos(S + V - \phi_r) + m \cos(S - U + \phi_r)}{2 \cos(U - \phi_r)} \right]^2 + \left[X - \frac{n \sin(S + V - \phi_r) + m \sin(S - U + \phi_r)}{2 \cos(U - \phi_r)} \right]^2 = \frac{n^2 + m^2 - 2mn \cos(V - U)}{4 \cos^2(U - \phi_r)} \quad (7)$$

This is a circle having a center at

$$45 \quad R_0 = \frac{n \cos(S + V - \phi_r) + m \cos(S - U + \phi_r)}{2 \cos(U - \phi_r)} \quad (8)$$

$$X_0 = \frac{n \sin(S + V - \phi_r) + m \sin(S - U + \phi_r)}{2 \cos(U - \phi_r)} \quad (9)$$

The slope of the line connecting the center to the origin is

$$S_0 = \tan^{-1} \frac{X_0}{R_0} =$$

$$55 \quad \frac{n \sin(S + V - \phi_r) + m \sin(S - U + \phi_r)}{n \cos(S + V - \phi_r) + m \cos(S - U + \phi_r)} \quad (10)$$

The displacement of the center from the origin is

$$D_0 = \sqrt{R_0^2 + X_0^2} =$$

$$\frac{\sqrt{n^2 + m^2 + 2mn \cos(U + V - 2\phi_r)}}{2 \cos(U - \phi_r)} \quad (11)$$

The radius of the circle is

$$Q_0 = \frac{\sqrt{n^2 + m^2 - 2mn \cos(V - U)}}{2 \cos(U - \phi_r)} \quad (12)$$

The intercepts of the circle on the center-axis, the center-axis being the line connecting the center and the origin, are

$$D_1 = D_0 + Q_0 = \frac{\sqrt{n^2 + m^2 + 2mn \cos(U + V - 2\phi_r)} + \sqrt{n^2 + m^2 - 2mn \cos(V - U)}}{2 \cos(U - \phi_r)} \quad (13)$$

$$D_2 = D_0 - Q_0 = \frac{\sqrt{n^2 + m^2 + 2mn \cos(U + V - 2\phi_r)} - \sqrt{n^2 + m^2 - 2mn \cos(V - U)}}{2 \cos(U - \phi_r)} \quad (14)$$

Equations 8 to 14 show that the characteristics of the response-circle of a wattmetric relay, energized as shown in Equations 2 and 3, are very complex quantities, when expressed in terms of the controllable variables, m , n , S , U and V .

In accordance with my present invention, however, I have discovered that very simple, practically usable relations may be obtained by making the angle U equal the angle ϕ_r in the element at which the maximum torque occurs, and by making the angle V always equal $180^\circ + U$. Expressed in equations, these essential conditions are

$$U = \phi_r \quad (15)$$

$$V = 180^\circ + \phi_r \quad (16)$$

By equating the torque-equation (4), to zero, in order to ascertain the balance-point, the coefficients g and h become immaterial, insofar as the size and position of the response-circle are concerned.

The relay-fluxes may then be expressed,

$$\phi_1 = E \angle S - mI \angle \theta \quad (2A)$$

$$\phi_2 = E \angle (S - \phi_r) + nI \angle (\theta - \phi_r) \quad (3A)$$

The center-line slope becomes

$$S_0 = S \quad (10A)$$

The center-line intercepts become

$$D_1 = n \quad (13A)$$

$$D_2 = -m \quad (13B)$$

Fig. 1 shows the application of these principles to a wattmetric (or product-responsive) relay-element W of the cosine type, that is, one in which the torque is a maximum when the two alternating quantities to be multiplied are in phase with each other, that is, when $\phi_r = 0$. The field windings of the directional or impedance element W in Fig. 1 comprise a field potential coil E_R and a field current coil I_R . The polarizing windings similarly comprise a polarizing potential coil E_0 and a polarizing current coil I_0 . The relay element W also has relay-contacts 3 for controlling a protective-relay circuit 4 for protecting an alternating-current line 5 .

A line-current transformer 6 derives an alternating relaying-current i from the line in response to the line-current, and supplies this current to two variable-ratio auxiliary transformers T_R and T_0 having adjustable taps m and n , respectively, for supplying the separately adjustable currents mi and nI to the current-coils I_R and I_0 , respectively.

The two potential coils E_R and E_0 are con-

nected in series, and are energized from a potential transformer 7 through a variable phase-shifter 8 and a fixed phase-controlling inductance 9 . The potential transformer 7 derives an alternating relaying-voltage E from the line 5 in response to the line-voltage.

Any suitable phase-shifter 8 may be utilized, for changing the phase-angle, without substantially changing the magnitude, of the voltage impressed thereon. The particular phase-shifter shown at 8 in Fig. 1 is one which is described and claimed in an application of H. J. Carlin, Serial No. 583,926, filed March 21, 1945, and assigned to the Westinghouse Electric Corporation.

It is capable of effecting a phase-shift of between 0° and some 30° , plus or minus, through a reversing-switch 11 . It comprises a mutual reactor M_1 having a primary winding 13 in series with the voltage-source E , and a secondary winding 14 connected across the voltage-source E through a large variable resistor R_1 .

The fixed inductance 9 is included in the potential-coil circuit in order to introduce a fixed phase-shift of approximately 90° in the potential-coil current. Thus, the two elements 8 and 9 together provide a phase-shift that can be varied between $S=60^\circ$ and $S=120^\circ$, using the terminology of Equations 2A and 3A.

The apparatus shown in Fig. 1 thus provides means whereby the center-line slope S of Equation 10A may be varied, by means of the variable phase-shifter 8 , without varying the center-line intercepts D_1 and D_2 . The major intercept D_1 may be varied, substantially independently of the minor intercept D_2 or the slope S_0 , by adjusting the tap n ; while the minor intercept D_2 may be similarly independently adjusted by adjusting the tap m .

The relay W in Fig. 1 is intended to be symbolic of any means for providing a torque which is proportional to the vector sum of the current mi and voltage $E \angle S$ in the field coils I_R and E_R , times the vector sum of the current nI and voltage $E \angle S$ in the polarizing coils I_0 and E_0 , times the cosine of the angle between them, or, in general, times any function of the angle between them. Other means may also be used.

For example, Fig. 2 illustrates the application of my invention to a sine-type wattmetric relay W^1 having two voltage-type windings ϕ_1 and ϕ_2 for developing a torque proportional to the product of the energizing-currents in said windings ϕ_1 and ϕ_2 , times the sine of the phase-angle between the impressed voltages. The relay W^1 has the relay-contacts 3 , which close when the relay responds.

In Fig. 2 the excitation is shown as being in response to current-compensated voltages. The same source of the adjustable-phase relaying-voltage $E \angle S$ is shown in Fig. 2, as in Fig. 1, comprising the potential transformer 7 , and the phase shifters 8 and 9 . The current-response, in

Fig. 2, is obtained by means of compensator-impedances; shown as two independently adjustable resistors R_m and R_n , connected in two branch-circuits in series with $E \angle S$, as shown at 21 and 22 , respectively, for energizing the relay-coils ϕ_1 and ϕ_2 , respectively. The line-current i

is circulated through the resistors R_n and R_m to produce the voltage-drops $+R_n I$ and $-R_m I$, respectively.

In Fig. 2, since the illustrated directional element W^1 is a sine-relay, the exciting-currents in the two coils ϕ_1 and ϕ_2 must be dephased by the angle 90° when the same voltage is impressed on each. To this end, I have shown a capacitor C_2 in series with the coil ϕ_2 , the relative numbers of turns of the two coils ϕ_1 and ϕ_2 being properly chosen so that the desired flux-magnitudes are obtained.

From the circuit in Fig. 2, it is evident that the flux

$$\phi_1 = E \angle S - R_m I \angle \theta \quad (2B)$$

is produced by the coil ϕ_1 , while the other coil ϕ_2 produces the flux

$$\phi_2 = (E \angle S + R_n I \angle \theta) \angle 90^\circ \quad (3B)$$

corresponding to Equations 2A and 3A when the relay-angle $\phi_r = 90^\circ$.

Thus, in Fig. 2, the slope of the center-line is controlled by adjusting the phase-shifter S , while the center-line intercepts D_1 and D_2 are independently controlled by adjusting R_n and R_m , respectively.

In Fig. 3, I have shown a typical response-circle 30, having a center C at (R_0, X_0) , a center-displacement and center-axis $\overline{CO} = D_0$, a center-axis slope S_0 , and center-axis intercepts D_1 and D_2 . The circle-radius is also indicated at Q_0 .

It will be noted that the angle S and the magnitudes m and n are relative values. The angle S refers to the angle by which the voltage-responsive excitation-component leads the current-responsive component, or the angle by which the latter lags the former, at unity power-factor. The coefficients m and n refer to the ratio of the relative magnitudes of current-response to voltage-response, or vice versa. The relations are general.

While I have illustrated my invention in two illustrative forms of embodiment, I wish it to be understood that the invention is susceptible of considerable variation in its forms of embodiment, and I desire that the appended claims shall be accorded the broadest interpretation consistent with their language.

I claim as my invention:

1. An adjustable distance-type product-responsive relay having two diverse cooperating alternating magnetic fluxes, means for so utilizing said fluxes as to produce a torque in response to the product of said fluxes, multiplied by $\cos(\phi_0 - \phi_r)$, where ϕ_0 is the angle between said two cooperating fluxes, and ϕ_r is the characteristic phase-angle of the relay, and two diverse flux-producing means for producing the respective fluxes, characterized by each of said flux-producing means comprising means for producing a voltage-responsive excitation-component in response to a line-derived voltage, means for producing a current-responsive excitation-component in response to a line-derived current, a common phase-shifter means for causing substantially the same phase-angle S to exist between the two excitation-components of each of

said cooperating fluxes at unity power-factor, said phase-shifter means being adjustable to vary said phase-angle S without substantially varying the relative magnitudes of said components, said flux-producing means including circuit-connection means for causing a phase-angle of substantially ϕ_r to exist between the two voltage-responsive excitation-components, and also between the two current-responsive excitation-components, of the two cooperating fluxes, and separate magnitude-adjusting means, one for each of said cooperating fluxes, for substantially independently adjusting the ratio of the relative magnitudes of current-response to voltage-response of each of said cooperative fluxes without substantially varying said phase-angle adjustments.

2. An adjustable distance-type product-responsive relay having two diverse cooperating alternating magnetic fluxes, means for so utilizing said fluxes as to produce a torque in response to the product of said fluxes, multiplied by $\cos(\phi_0 - \phi_r)$, where ϕ_0 is the angle between said two cooperating fluxes, and ϕ_r is the characteristic phase-angle of the relay, and two diverse flux-producing means for producing the respective fluxes, characterized by each of said flux-producing means comprising means for producing a voltage-responsive excitation-component in response to a line-derived voltage, means for producing a current-responsive excitation-component in response to a line-derived current, a common phase-shifter means for causing substantially the same phase-angle S to exist between the two excitation-components of each of said cooperating fluxes at unity power-factor, said phase-shifter means being adjustable to vary said phase-angle S without substantially varying the relative magnitudes of said components, said flux-producing means including circuit-connection means for causing a phase-angle of substantially ϕ_r to exist between the two voltage-responsive excitation-components, and also between the two current-responsive excitation-components, of the two cooperating fluxes, and separate magnitude-adjusting means, one for each of said cooperating fluxes, for substantially independently adjusting the magnitudes of the current-responses of the respective fluxes without substantially varying the phase-angle adjustments.
